MICHAEL F. OWENS, OF HARTFORD, CONNECTICUT, ASSIGNOR TO AUTOMATIC REFRIGERATING COMPANY, OF HARTFORD, CONNECTICUT, A CORPORATION OF NEW JERSEY.

ELECTRICAL LOW-SPEED CUT-OUT.

1,047,557.

Specification of Letters Patent. Patented Dec. 17, 1912.

Application filed November 23, 1911. Serial No. 661,978.

To all whom it may concern:

Be it known that I, MICHAEL F. OWENS, a citizen of the United States, and resident of Hartford, in the county of Hartford and State of Connecticut, have invented certain new and useful Improvements in Electrical Low-Speed Cut-Outs, of which the following is a full and clear specification, illustrated in the accompanying drawings, the particular novel features of the invention being more fully pointed out in the annexed claims.

My invention relates in general to cut out mechanism which comes into operation when the motor for driving machinery of any kind fails to start within a predetermined time.

In particular my invention relates to a mechanism which enables me to cut out the operation of the motor even if the latter should complete its starting within the predetermined time but, through some cause, the driven mechanism should not readily start with the motor. As an example in refrigerating apparatus the compressor is frequently driven by an electromotor by means of a belt. Now, aside from the danger that the motor itself should not complete its starting period within a predetermined time through some cause in the electromotor itself, so that it should be immediately cut off from the current supply, there is also the danger that, while the motor may complete its starting period within the predetermined time, the belt which drives the compressor may slip so that within this time the compressor has not attained its normal speed. This puts an undue strain on the driving belt and therefore also in this case the motor should be cut off immediately from the current supply. The apparatus illustrated, is particularly designed to cut the motor off when the driven machinery fails to start, notwithstanding the normal starting of the motor, and therefore the apparatus is connected to the power transmission system and only indirectly to the motor, but it is obvious that the apparatus without changing its arrangement in its essential features, may be also employed directly at the motor and directly connected with it so that it supervises the speed of the motor alone.

In the accompanying drawings, I have shown substantially diagrammatically my novel mechanism in connection with a wiring system for an electromotor particularly adapted to respond to the actions of the thermostat of a refrigerating system, and it is assumed thereby that the cut out control mechanism is belt connected to the compressor.

The construction of the cut out mechanism which is indicated at 1 in the drawings is as follows: On base plate 2 are mounted two uprights 3 and 4 in and between which a shaft 5 is journaled which carries belt pulley 6 by means of which shaft 5 may be driven from the compressor D, the speed of which the device is to supervise. Connected with pulley 6 is a governor 7 so that the collar 8 of the governor may slide toward and away from pulley 6, according to whether the pulley runs fast or slow. The governor springs 9 normally tend to move a collar 8 away from pulley 6. Upright 4 is longer than upright 3 and carries a solenoid coil 10, the core 11 of which carries at its upper end a piston 12 disposed in a dash pot cylinder 13 with a valve 14 at its upper end. The dash pot cylinder 13 is open at its lower end. The armature or core 11 has also a downward extension 15 which is guided in a bracket 16, integral with upright 4 the lower end of this extension carrying a roller 17 which, when solenoid 10 is deenergized so that the armature 11 is in its lowermost position as shown, is in the path of collar 8 of the governor and prevents this collar from further sliding to the left under the tension of springs 9. However, as soon as pulley 6 has attained the proper speed collar 8 is moved to the right and away from roller 17. When the solenoid 10 is energized in the manner which will be described presently, the armature 11 is drawn in against the resistance of the dash pot so that only after a predetermined time, controlled by the setting of valve 14, armature 12 will be completely drawn in so that roller 17 is removed thereby from the path of collar 8, and thus the latter is enabled to further travel to the left under the influence of springs 9 should the pulley 6 not rotate fast enough to cause the governor balls 18 to

draw the collar to the right. Adjacent to collar 8, but slightly farther to the left of roller 17 is mounted a bell crank 19, pivotally supported on upright 4. The vertical shank of the bell crank stands in the path of travel of collar 8, whereas the horizontal end carries a contact arm 20 insulated from the bell crank. This contact arm coöperates with a complementary element 21 mounted 5 on a support 22 which in turn is fastened to upright 4, but insulated therefrom as shown. If now, as previously described, through energizing of solenoid 10, roller 17 should be moved out of the path of collar 8 and 10 through lack of speed of the governor this collar should be thus permitted to further slide to the left beyond the margin normally set by roller 17, it will strike the upright shank of bell crank 19 and rock it thereby, 15 interrupting the contact between contact elements 20 and 21 which, as shown, are normally closed.

The apparatus which I have just described may be employed for instance in a 20 circuit arrangement for controlling the cutting in and out of a motor which may drive a compressor for refrigerating systems as follows: In the drawings M indicates the motor which drives the compressor D as 25 shown. From pulley 41, mounted on the compressor shaft 40, a small belt runs over pulley 6 of the cut out device. The mains for supplying current to the motor are indicated at *a*, *b*, *c* and *d*, motor M being illustrated as a two-phase motor. 25 is a main switch which is controlled by solenoid 26. The armature 27 of the solenoid which is shown in deenergized position is connected at its upper end with switch 25 which is 30 shown open and at its lower end it has attached to it two contact bars 28 and 29 which make contact alternately; bar 29 makes contact when the solenoid 26 is deenergized and 28 closes its contacts when 35 the solenoid is energized. 30 represents a thermostat which, under normal conditions, controls the starting and stopping of the motor according to the requirements of the refrigerating system. In this thermostat T 40 represents the movable thermostat arm, H the contact coöperating with the arm when the motor should start, and C the contact which coöperates with arm T when the motor should stop. The elements are all shown 45 in resting position. If now the thermostat arm calls for starting of the motor and thus moves over to contact H the following circuit is closed: from main *b* over contact *e* of switch 25, line 31, across contact bar 29 50 which is then closed, line 32, contact H, thermostat arm T, line 33, contact arm 20 of the cut out control, contact spring 22, line 34, solenoid coil 26, resistance *y* main *a*. The solenoid 26 being energized thereby

closes its switch 25 so that motor M receives current through the mains *a*, *b*, *c*, and *d*. The closing of switch 25 also closes a shunt circuit between mains *a* and *b* which branches off from main *a* by way of line 24, solenoid coil 10 of the governor cut out, line 35, and back to switch 25 and main *b*. The closing of the motor circuit effects the starting of the motor and it is assumed that normally the driven compressor will start its operation with the motor so that gradually pulley 6 is driven faster and faster, whereby collar 8 of the governor is removed from the roller 17. The simultaneous energizing of solenoid 10, previously mentioned, also starts the upward movement of its armature 11 against the resistance of the dash pot, whereby gradually roller 17 is removed from the path of collar 8. The retarding action of the dash pot thus prevents an immediate removal of roller 17 at a time when, owing to the inertia of the system, the pulley 6 cannot possibly have attained sufficient speed to move the collar 8 to the right against the tension of springs 9. The upward movement of armature 27 of switch solenoid 26 also removes contact bar 29 from its contacts and presses contact bar 28 upon its contacts so that the current which runs through lines 33 and 34 runs around thermostat 32 by way of line 31, resistance *x*, bar 28, line 36 to line 33. This prevents current permanently flowing through the thermostat. If now the driven machinery should have failed to attain its normal speed, after the dash pot has removed roller 17 from the path of collar 8, within predetermined time, for instance on account of slipping or breaking of the belt, the slowing down of pulley 6 permits collar 8, under the action of springs 9, to freely slide to the left where it will strike bell crank 19 and by rocking it interrupt contacts 20, 21. This opens the circuit through the switch solenoid 26 so that the latter will drop its armature 27 and open the main switch 25 and stop the motor. If normal running conditions exist, that is when the driven machine has attained its speed and collar 8 has been drawn to the right, and now the thermostat arm T moves to the left onto its contact C, whereby the solenoid coil 26 is short-circuited by the short circuit main *a*, resistance *y*, line 37, contact C, arm T, line 36, bar 28, resistance *x*, line 31, main *b*, in order to stop the motor, main switch 25 will first open. This also immediately opens the shunt circuit 24, 35 through the governor solenoid 10, and the dash pot not offering any resistance against the downward movement of its armature 11, this armature will quickly drop and move roller 17 into the path of collar 8. The momentum of the driven machinery will not permit pulley 6 to stop immediately so that collar 8 will only

gradually move back to the left long after roller 17 has moved into its path and thus when the governor comes to a standstill, collar 8 will be prevented from further moving 5 to the left and striking bell crank 19 which, by gravity, or other suitable means, always tends to close contacts 20 and 21. It is obvious from the description of the apparatus that it will also stop the motor when in 10 normal running condition if the belt should suddenly slip off or break through some cause, because then the motor current being still turned on, solenoid 10 is fully energized and has lifted roller 17, while then the governor collar 8 is free to move to the left and strike the bell crank 19 when the governor slides down.

What I claim is:

1. In a power transmission system having a motor and machinery driven thereby, a cut out mechanism comprising an element responsive to speed variation and operated by said transmission system, an element controlling the stopping of the motor, said speed responsive element adapted to operate said stopping element when the speed of the system falls below the desired limit, and means removably disposed between said speed responsive element and said stopping 25 element for preventing the actuation of said stopping element during a predetermined time to permit starting and accelerating of said system, and means for removing said interposed means within a predetermined 30 time after the motor has started.

2. In a power transmission system having a motor and machinery driven thereby, a cut out mechanism comprising an element responsive to speed variation and operated 40 by said transmission system, and an element controlling the stopping of the motor, said speed responsive element adapted to operate said stopping element when the speed of the system falls below the desired 45 limit, and dash-pot-controlled means removably disposed between said speed responsive element and said stopping element for preventing the actuation of said stopping element during a predetermined time 50 to permit starting and accelerating of said system and means for removing said dash pot controlled means after the motor has started.

3. In a power transmission system having a motor and machinery driven thereby, a cut out mechanism comprising an element responsive to speed variation and operated by said transmission system, and an element controlling the stopping of the motor, said speed responsive element adapted to operate said stopping element when the speed of the system falls below the desired 55 limit, and dash-pot-controlled means normally interposed between said two elements

for preventing the actuation of said stopping element, said means adapted to move away from its normal position within a predetermined time after the starting of the motor, to permit actuation of said stopping element when the speed of the system falls 65 below the desired limit and means for actuating said dash pot controlled means when the motor starts.

4. In a power transmission system having a motor and machinery driven thereby, a 75 cut out mechanism comprising a governor operated by said transmission system, and a motor cut out, said governor adapted to operate said cut out below the desired speed limit of the system, and a dash-pot-controlled element disposed between said governor and said cut out to prevent operation 80 of the latter before the starting and during the acceleration period of the system, said element having means actuated at the starting of the motor and adapted to move said element from its normal position against the resistance of the dash-pot with the starting 85 of the motor.

5. In a power transmission system having 90 an electromotor and mechanism driven thereby, a cut out mechanism comprising a governor operated by said transmission system, and an electric motor cut out, said governor adapted to operate said cut out below 95 the desired speed limit of the system, and a solenoid electrically connected to the motor to receive current simultaneously with the motor and having one end of its armature in deenergized position located between said 100 governor and said cut out to prevent actuation of the latter before and during the starting period of the motor, and having its other end connected with a dash pot, said armature starting to move away from its 105 normal position against the resistance of the dash pot when the solenoid is energized and the motor starts, and permitting said governor after a predetermined time controlled by said dash pot, to operate said cut out if 110 the speed of the motor should fall below the desired limit.

6. In a power transmission system having an electromotor and mechanism driven thereby, a cut out mechanism comprising a 115 governor operated by said transmission system, and an electric motor cut out consisting of a switch having an actuating arm in the path of a sliding collar attached to said governor to permit said governor to open 120 said switch below the desired speed limit of the system and a solenoid electrically connected to the motor to receive current simultaneously with the motor and having one end of its armature in deenergized position located in the path of said collar to prevent its engagement with said actuating arm before and during the starting period of the 125

motor and having its other end connected with a dash pot, said armature starting to move away from said collar against the resistance of the dash pot when the solenoid 5 is energized and the motor starts and permitting said collar after a predetermined time controlled by said dash pot to engage

said actuating arm to open the switch and cut out the motor if the speed of the system should fall below the desired limit.
